UNITED STATES PATENT OFFICE.

MAX C. BRUHN AND GEORGE F. MCGILL, OF CHICAGO, ILLINOIS.

CHANGE-MAKER.

1,272,372.

Specification of Letters Patent. Patented July 16, 1918.

Application filed May 5, 1916. Serial No. 95,580.

To all whom it may concern:

Be it known that we, MAX C. BRUHN and GEORGE F. MCGILL, citizens of the United States, residing at Chicago, in the county of Cook and State of Illinois, have invented certain new and useful Improvements in Change-Makers, of which the following is a specification.

This invention relates to a holder and dispenser of coins for making change, and the principal object of the invention is to provide a new and improved construction, combination and arrangement of parts for accomplishing the desired result.

In the drawings, Figure 1 is a front elevation with parts broken away, of a change maker constructed in accordance with the principles of our invention; Fig. 2 is a sectional view; Fig. 3 is a sectional view taken on line 3—3 of Fig. 2; Fig. 4 is a sectional view taken on line 4—4 of Fig. 2; Fig. 5 is a plan view of a portion of the operating mechanism; and Fig. 6 is a perspective of one of the operating mechanisms.

In the present invention, the numeral 1 designates generally a casing which may be made of any suitable material such as metal or wood, and in the present form the casing is provided with a removable front 2, having a hinged top 3 which is held in place by a spring catch 4 at one or both ends of the casing.

Supported by the casing are a plurality of coin-holding tubes of different sizes, each 35 opened on one side and adapted to contain coins or checks of different sizes. These tubes are rigidly supported by the casing and are inclined from the vertical, as shown more clearly in Fig. 2, with a rounded portion 6 adjacent the bottom of each tube bent at a slightly different angle, more nearly upright than the remainder of the tube. This rounded portion 6 also conforms more nearly to the curvature of the coin for which the 45 particular tube is designed and intended.

At the bottoms of the tubes 5 is a plate 7 for supporting the stack of coins in each tube. The inclination of the tubes from the vertical position takes some of the weight 50 of the stack of coins from the bottom plate so that no matter how high the coins are filled in the tube the weight on the bottom

plate 7, and consequently on the bottom coin, will not be excessive. This bottom plate 7 is formed between the sides of each 55 tube with a notch 8 from the center of which extends a curved slot 9. A shaft or pin 10 is secured to the bottom plate 7 and depends from the plate at approximately the center of curvature of the slot 9. Pivoted 60 on the pin is an ejecting member 11 pressed upwardly against or in the direction of the plate 7 by means of a spring 12 which is held on the pin 10 by nuts 13 or other suitable fastening means operable also to adjust 65 the tension of the spring.

At the rear of each coin tube 5 is a slot 14 in the bottom plate 7. Through this slot extends one arm 15 of a key-lever 16 which is pivoted on a shaft 17 mounted below the 70 coin tubes in brackets 18. The other arm 19 of each key-lever extends through a suitable slot 20 in the front of the casing and is provided at its outer end with a button or finger-piece 21. A spring 22 is mounted on 75 the shaft 17 and the ends are suitably engaged to press the arm 15 of the key-lever to the rear of the slot 14.

Each projecting member 11, as shown more clearly in Fig. 5, is provided with an 80 irregular slot 23 which extends at an angle to the slot 14 in the bottom plate 7 but crosses it, so that the extremity of the arm 15 of the key-lever 16 also extends through the slot 23 of the ejecting member. Projecting upwardly from the ejecting member 11 through the slot 9 of the bottom plate 7 is an ejecting projection 24 which is cut away at the rear, as designated by the numeral 25, and as viewed in Fig. 6, so that in 85 the forward movement in the slot 9 the projection 24 will engage the rear of the lowermost coin at the bottom of the tube, but in the other direction of movement the beveled edge 25 constituting the heel of the projection 24 will ride yieldingly under the lowermost coin because of the yielding action of spring 12 which tends to press the ejecting member 11 upwardly against the bottom plate 7. Also extending upwardly from the 90 front of each ejecting member 11 and forming an integral part thereof is a projection 26, the top of which is in the plane or just above the plane of the top of the bottom

plate 7. At the rear of this projection 26 is an inclined portion 27 which extends below the top of the bottom plate at all times. The normal position of this projection 26 is in the notch 8 at the front of each coin tube, substantially in front of the slot 9. The object of the projection 26 is to engage the lower and outer edge of a coin positioning it in the tube by tipping the front of the 10 coin outwardly, thus insuring that it rests directly upon the top of plate 7 so that the rear of the coin will be in position to be engaged by the ejector 24 upon its forward movement. Without this projection 26 it 15 might happen that if there were only a few coins, or only a single coin in the tube it might have tipped downwardly at the forward side of the coin and therefore the ejector in moving forwardly would fail to 20 engage the rear of the coin and hence would not eject it; but by providing a projection 26 at the front of each coin tube the coins are positively positioned and properly held upon the bottom plate for engagement by 25 the ejector 24.

In order to prevent the ejection of more than one coin from each tube upon a single operation of the ejector, a detent plate 28 (see Fig. 4) is attached to the lid 3, which 30 has projections 29 extending downwardly to a point above the top of the bottom plate 7, depending upon the thickness of the coin for which the tube directly opposite any one of the projections 29 is designed. These projections 29 permit the dispensing of a single coin but prevent more than one coin from being ejected from the tube at the same time.

Arranged at the front of the tubes 5 and within the casing 1 just below the cover 3 40 is an inclined chute 30 which extends through an opening at the end of the casing for discharging the coins into another chute 31 attachable to the outside of the casing. This chute 31 discharges the coins into 45 a receptacle 32 preferably in the form of a shallow-dish, from which they are easily removable. This receptacle 32 may be made removable by providing it with a bracket 33 into which a tongue 34 secured to the chute 31 extends. At the bottom of the 50 chute 31 or secured to the receptacle 32 is a bridge 35 extending substantially the width of the chute 31 to engage and prevent coins from rolling down the chute thus causing 55 them to slide into the receptacle so they will not jump over or out of it.

The arrangement of the chute 31 and receptacle 32 is optional, depending upon the place in which the change maker is used. 60 The specific construction above described is particularly adapted for use in connection with cashiers' desks and the like where the change is to be discharged from one side of the partition to the other, the change 65 maker being located on one side of the par-

tion and the receptacle 32 or a portion of the same, on the other side.

From the above description it is obvious that a depression of any one or more of the keys will dispense the corresponding coin or 70 coins from the bottom of the tube or tubes 5 into the center chute 30. Only one coin will be discharged from each tube for each actuation of the proper key-lever, but of course 75 all or any of the key-levers may be depressed at the same time. Upon the return of the ejecting member not only will the ejector 24 pass vertically under the stack of coins without disturbing them, because of the pressure 80 spring 12, but also all of the coins, and particularly the lowermost coin of each chute will be properly positioned by the projection 26 of the ejecting member so that the lowermost coin will be positively placed and held in position for engagement by the 85 ejector upon its next forward movement. If the coins become clogged in any of the tubes 5, in the chute 30, or if it is desired to insert or remove coins from the tubes 5 it is necessary only to raise the cover 3 by disengaging 90 the latch 4 and to manipulate the coins as desired.

We claim:

1. In a change maker, a coin tube and a bottom support for a stack of coins in the 95 tube, and a movable ejector pivoted at one side of the coin stack for engaging the lowermost coin in one direction of movement, yieldingly supported for depression below the lowermost coin in the other direction of movement.

2. In a change maker, a bottom support for a stack of coins having a slot therein, an ejector pivoted at one side of and movable in the slot with a projection for engaging the lowermost coin in one direction of movement, and a yielding support for the ejector whereby it is depressed by engagement with the lowermost coin in the other direction of movement.

3. In a change maker, a support for a stack of coins having a curved slot therein, an ejector pivotally mounted at one end of the slot having a projection movable in the slot to engage the lowermost coin in one direction of movement, a spring to press the ejector yieldingly upward whereby the ejector in moving in the other direction will be depressed by contact with the lowermost coin, until the projection is moved behind 115 the coin.

4. In a change maker, a bottom support for a stack of coins having a curved slot therein, a member depending from the support, an ejector pivoted on the member having a projection movable in the slot and adapted to engage the lowermost coin in one direction of movement, and a spring mounted and adjustable in tension on the member tending to press the ejector upwardly, the 125 130

said projection having an inclined rear portion which depresses the ejector when the projection is moved in the other direction.

5. In a change maker, a coin tube and a bottom support for a stack of coins in the tube, an ejector for engaging the lowermost coin in one direction of movement and ejecting it from the front of the tube, and a yielding projection movable simultaneously with the ejector and above the plane of the support to engage the bottom and positively position the front side of each of the lowermost coins in the tube where they will be engaged by the ejector in its next movement.

15. 6. In a change maker, a coin tube and a bottom support for a stack of coins in the tube, a movable ejector for engaging the lowermost coin in one direction of movement, and a member movable with the ejector for yieldingly engaging the lowermost coin in the other direction of movement of the ejector to engage the bottom of and position the lowermost coin for the next operative movement of the ejector.

25. 7. In a change maker, a coin tube and a bottom support for a stack of coins in the tube, a movable ejector for engaging the lowermost coin in one direction of movement, having an integral projection which 30 yieldingly engages the lowermost coin in the other direction of movement of the ejector for positioning the coin to tilt and hold it straight and insure its engagement upon the operative movement of the ejector.

35. 8. A change maker comprising a coin tube, a bottom support, a movable ejector adapted to engage the lowermost coin in one direction of movement, a member for engaging the bottom and positively positioning the lowermost coin for engagement by the ejector in the other direction of movement of the ejector, and a yielding support for the ejector whereby it will be depressed by engagement with the lowermost coin in the non-ejecting direction of movement.

45. 9. In a change maker, an inclined coin tube and a bottom support therefor, an ejector movable in one direction to engage the lowermost coin and discharge it from the tube in one direction of movement, with a projection to yieldingly engage the bottom of the lowermost coin at its front side and positively position it in the bottom of the tube in the non-ejecting movement of the ejector so that the lowermost coin will be positively held in position for engagement by the ejector upon its next ejecting movement.

50. 10. In a change maker, a casing, a plurality of open coin tubes supported by the casing in a substantially upright position, a common plate for supporting a stack of coins in each tube, means for ejecting the lowermost coin from each tube, a hinged cover disposed over the lower portion of

the tube, and a plate carried thereby having projections disposed at the open sides of the tube for preventing more than one coin from being simultaneously ejected from any one of the tubes.

55. 11. In a change maker, the combination with a plurality of upright tubes, of a plate for supporting coins in the tubes, having a recess at the front of each tube and a slot extending therefrom, the part of the plate adjacent the recess being sufficient to support the coins, an ejector operating in the said slot to engage the lowermost coin in each tube, a member movable with the ejector but normally positioned in the said recess to support the coins in the tube and to engage the front portion of the bottom of the lowermost coin to insure that it is supported at the rear of the tube by the bottom plate.

60. 12. In a change maker, a coin tube and a bottom plate for supporting coins in the tube, the said plate being formed with a recess at the front of the tube over which the coins extend, an ejector movable to engage the lowermost coin having a projection movable therewith and normally seated in the recess at the front of the tube for engaging the bottom of and yieldingly positioning the lowermost coin on the bottom plate to be engaged by the ejector and movable to free the coin for discharging it when the ejector is operated.

65. 13. In a change maker, an upright coin tube and a bottom plate for supporting the coins having a recess at the front of the tube over which a portion of the lowermost coin extends, an ejector for engaging the lowermost coin at the rear of the tube with a projection movable therewith for normally supporting and yieldingly engaging the front of the lowermost coin and movable with the ejector for discharging the coin, and means to engage the coins above the lowermost one in the tube for preventing more than one coin from being actuated upon a single movement of the ejector.

70. 14. In a change maker, a casing, upright coin tubes supported by the casing and open at the front sides, means for ejecting the lowermost coin from each tube, a common chute into which the coins from each tube are discharged, extending downwardly from the tube at one end through the other end of the casing, a hinged lid for covering the lowermost ends of the tubes, the upper ends of the tubes extending above the lid, a cover extending over the said chute, and means in connection with the lid for preventing more than one coin from being ejected simultaneously from each tube.

75. 15. In a change maker, the combination with a coin tube, of a fixed bottom plate therefor having a slot, an ejector adapted to engage the lowermost coin in the tube

pivoted on the bottom plate with a slot extending across the slot in the plate at an angle thereto, and an actuating lever for the ejector having an arm extending through the slot of the bottom plate and the slot of the ejector so that the movement of the arm will cause the movement of the ejector.

16. In a change maker, a coin tube and a bottom plate for supporting a stack of coins, the said plate being provided with an elongated slot, an ejector yieldingly supported below the plate for pivotal movement and movement toward and from the plate, the said ejector having a slot which extends at an angle to the slot of the plate, and an actuating lever for the ejector having an arm extending through the slot of the plate and the slot of the ejector, for moving the ejector in accordance with the movement of the arm.

17. In a change maker, a casing having a

hinged top, a plurality of upright coin tubes secured to the casing, and extending above and below the hinged top, the fronts of the tubes being open and contiguous to the adjacent edge of the top, a coin ejector at the bottom of each tube, a common chute into which the ejectors discharge the coins, the chute extending from the end of the casing, a plate secured to the edge of the top adjacent the tubes for preventing more than one coin from being simultaneously ejected from each tube, a coin receptacle arranged at the back of the casing, and a connecting chute extending from the first-named chute and discharging into the receptacle.

In testimony whereof we have signed our names to this specification, on this 27th day of April A. D. 1916.

MAX C. BRUHN.
GEORGE F. MCGILL.
